Primary Examiner — Jae Liang*Assistant Examiner* — Samantha Lynne Brodowski(74) *Attorney, Agent, or Firm* — Mai D. Lauer; Westman, Champkin & Koehler P.A.**CLAIM**

The ornamental design for a tag-loop carrier assembly as shown and described.

DESCRIPTION

FIG. 1 is a front view of a first embodiment thereof;
FIG. 2 is a back view thereof;
FIG. 3 is a top view thereof;
FIG. 4 is a bottom view thereof;
FIG. 5 is a side view thereof, as taken from the left side of FIG. 1;
FIG. 6 is a side view thereof; as taken from the right side of FIG. 1;
FIG. 7 is a sectional view as taken along lines 7-7 in FIG. 1;
FIG. 8 is a front view of a second embodiment thereof;
FIG. 9 is a back view thereof;
FIG. 10 is a top view thereof;
FIG. 11 is a bottom view thereof;
FIG. 12 is a side view thereof, as taken from the left side of FIG. 8;
FIG. 13 is a side view thereof; as taken from the right side of FIG. 8; and,
FIG. 14 is a sectional view as taken along lines 14-14 in FIG. 8.
The evenly spaced broken lines are for the purposes of illustrating portions of the carrier and form no part of the claimed design. The dot-dash-dot lines in the drawings indicate that any portion of the article beyond what is shown forms no part of the claimed design.

1 Claim, 4 Drawing Sheets**Related U.S. Application Data**

Jul. 17, 2014, now abandoned, which is a division of application No. 29/437,913, filed on Nov. 21, 2012, now Pat. No. Des. 712,154.
